US00D799545S

(12) **United States Design Patent** (10) **Patent No.:** **US D799,545 S**
(45) **Date of Patent:** **** Oct. 10, 2017**

(54) **DISPLAY SCREEN OR PORTION THEREOF
WITH ICON**

(71) Applicant: **Apple Inc.**, Cupertino, CA (US)

(72) Inventors: **Aurelio Guzmán**, San Jose, CA (US);
Wan Si Wan, Sunnyvale, CA (US);
Christopher Wilson, San Francisco,
CA (US)

(73) Assignee: **Apple Inc.**, Cupertino, CA (US)

(**) Term: **15 Years**

(21) Appl. No.: **29/565,225**

(22) Filed: **May 18, 2016**

(51) **LOC (10) Cl.** **14-04**

(52) **U.S. Cl.**

USPC **D14/492**; D14/489

(58) **Field of Classification Search**

USPC D14/489-495
CPC G06F 3/167; G06F 3/048; G06F 3/0481;

(57) **CLAIM**

The ornamental design for a display screen or portion thereof with icon, as shown and described.

DESCRIPTION

The file of this patent contains at least one drawing executed in color. Copies of this patent with color drawings will be provided by the Patent and Trademark Office upon request and payment of the necessary fee.

The FIGURE is a front view of a display screen or portion thereof with icon showing the claimed design.

The broken lines in the FIGURE show a display screen or portion thereof, and form no part of the claimed design.
